AIRPLANE LANDING FIELD

Filed Nov. 11, 1929

UNITED STATES PATENT OFFICE

HARRY CLAYTON BELLEVILLE, OF OAKLAND, CALIFORNIA

AIRPLANE LANDING FIELD

Application filed November 11, 1929. Serial No. 406,445.

My invention relates to improvements in airplane landing fields, and it consists in the combinations, constructions and arrangements hereinafter described and claimed.

5 An object of my invention is to provide an airplane landing field that is buoyant and anchored to the ground or other suitable object by a cable that may be wound or un wound from a drum for raising or lowering 10 the landing field. The field is preferably circular in shape and has a slight crown effect which will cause airplanes to tend to run upwardly toward the top of the crown when 15 landing upon the field, and in this way the planes will be quickly brought to a stop.

A further object of my invention is to provide a novel vane that will always cause the entrance of the field to head away from the 20 wind so that planes in landing may fly into the wind and still enter the field at the entrance thereof.

The buoyant part of the device resembles 25 an inverted cone, and the cable that secures the device against floating away permits it to move with the plane when the plane lands, and this will permit the plane to come to an almost immediate stop upon landing, any movement of the plane after landing causing 30 the field to move therewith.

I provide a landing field that is supported by air, and this field protects the gas bags disposed therebeneath.

Other objects and advantages will appear 35 as the specification proceeds, and the novel features of the device will be particularly pointed out in the claims hereto annexed.

My invention is illustrated in the accompanying drawings, in which:

40 Figure 1 is a perspective view of the device.

Figure 2 is a top plan view, and

Figure 3 is a transverse section through the device.

45 In carrying out my invention I provide a landing field indicated generally at 1 that is preferably circular in shape. A circumference of three hundred feet will provide a landing field of sufficient size to accommodate an airplane. The field 1 is preferably formed of

55 canvas 2, and this canvas has a top and a bottom for forming an air pocket 3. A cable 4 in the shape of a circle holds the field in the proper shape, and flexible strands 5 (see Figure 3) connect the top and bottom of the canvas bag 2 so as to limit the upward movement of the top of the bag. The strands provide a crown effect to the field for a purpose hereinafter described. Any means not shown 60 may be used for pumping air into the bag 2 for keeping the field substantially rigid and at the same time have enough give to it to permit an airplane to land with very little jarring.

Beneath the field 1 I dispose a plurality of 65 gas bags 6. These are preferably provided with square tops that bear against the underside of the canvas bag 2. A suitable netting 7 (see Figure 1) encloses the gas bags and is secured to the rim of the field so as to 70 provide a cone-shaped structure. The netting 7 carries a ring 8 at its apex, and this ring is secured to a cable 9 that extends down to a drum 10. The cable 9 may be wound upon or unwound from the drum 10 by means 75 of an electric motor 11 or other suitable mechanism.

I provide novel means for causing the entrance to the field 1 to always head away 80 from the wind so that planes in entering the field can pass through the entrance and at the same time head into the wind. This means comprises a telescoping boom pole 12 that is hinged at 13 adjacent to the apex of the buoyant device. An air pipe 14 communicates 85 with the interior of the hollow boom pole, and the joints of the various sections are so arranged as to make them air-tight structure. The ends of the boom pole are closed. When air is pumped into the pole through the pipe 90 14 by any means not shown, the pole will be elongated. The reverse is true when air is sucked out of the pole.

Two triangularly-shaped pieces of canvas 95 15 and 16 or other suitable material are secured to the boom pole 12 by rings 17 that in turn are attached to the pieces 15 and 16. The tops of the pieces 15 and 16 are attached to the netting 7 near the rim of the field 1 as shown in Figures 1 and 3. The edges 18 100

of the pieces 15 and 16 may be secured to the netting 7 and extend down to the ring 8.

From the foregoing description of the various parts of the device, the operation thereof 5 may be readily understood.

The wind is blowing from the left in Figure 1, and the strips 15 and 16 act as vanes for always causing the boom 12 to head away from the wind. The entrance X of the field 10 1 is disposed above the boom 12, and it will therefore be seen that a shifting of the wind will shift the vanes 15 and 16 and will likewise swing the entrance X so as to face away from the wind. In this way, an airplane Y 15 may head into the wind when landing upon the field.

The plane in landing will start to move up toward the top of the crown of the field. The entire field will also move with the plane to a 20 certain extent, and this will permit the plane to come to a quicker stop with respect to the field. The strips 15 and 16 will cause the field to incline slightly so as to offer a greater climbing angle for the landing plane. The 25 canvas pieces 15 and 16 have enough give to them to permit the boom 12 to be swung about its pivot a slight distance by means of a cable 19 that is secured to the end 20 of the boom and is passed over an idler pulley 21. The 30 boom may also be shortened when it is desired to lessen the effective area of the strips 15 and 16.

Although I have shown and described one embodiment of my invention, it is to be understood that the same is susceptible of various changes, and I reserve the right to employ such changes as may come within the scope of the invention as claimed.

I claim:

40 1. An airplane landing field comprising a lighter than air supporting member, and an air filled member disposed on the first member and having an upper surface designed to support an airplane.

45 2. An airplane landing field comprising a lighter than air supporting member, and an air filled member disposed on the first member and having an upper surface designed to support an airplane, the top of the second named 50 member being crown-shaped.

3. An airplane landing field comprising an air inflated member having an upper surface designed to support an airplane, means for holding the top of the member in a convex shape, and a plurality of lighter than air members supporting the air inflated member.

4. An airplane landing field comprising an air inflated member having an upper surface designed to support an airplane, means for 60 holding the top of the member in a convex shape, a plurality of lighter than air members supporting the air inflated member, a netting for enclosing the lighter than air members, and a cable secured to the netting 65 and to an anchoring object.

5. An airplane landing field comprising an air inflated member having an upper surface for supporting airplanes, said surface having an airplane entrance, a lighter than air supporting member disposed beneath the first member for lifting it, and means for causing the field entrance to always face away from the wind.

6. An airplane landing field comprising an air inflated member having an upper surface 75 for supporting airplanes, said surface having an airplane entrance, a lighter than air supporting member disposed beneath the first member for lifting it, means for causing the field entrance to always face away from the wind, said means comprising a boom pole supported by said second-named member, and vane-like members extending from the boom pole to the second-named member for causing the field entrance to face away from the wind.

7. An airplane landing field comprising an air inflated member having a circular-shaped upper surface for supporting airplanes, lighter than air supporting members disposed beneath the first-named member, a netting enclosing said last-named members and being conical in shape, a cable secured to the apex of the netting, means for winding in or unwinding the cable so as to raise or lower the landing field, a boom pole secured to the apex of the netting, and vane-like members secured to the pole and to the netting.

8. An airplane landing field comprising an air inflated member having a circular-shaped upper surface for supporting airplanes, lighter than air supporting members disposed beneath the first-named member, a netting enclosing said last-named members and being conical in shape, a cable secured to the apex of the netting, means for winding in or unwinding the cable so as to raise or lower the landing field, a boom pole secured to the apex of the netting, vane-like members secured to the pole and to the netting, said pole being telescopic, and means for changing the length of the pole.

9. An airplane landing field comprising an air inflated member having an upper surface for supporting airplanes, said surface having an airplane entrance, a lighter than air supporting member disposed beneath the first member for lifting it, and vane-like members for causing the field entrance to face away from the wind.

HARRY CLAYTON BELLEVILLE.
